US00D563362S

(12) **United States Design Patent** (10) **Patent No.:** **US D563,362 S**
LaDelfa (45) **Date of Patent:** **** Mar. 4, 2008**

(54) **PERSONAL DIGITAL ASSISTANT CAMERA
MOBILE PHONE**

(76) Inventor: **Paul LaDelfa**, 1333 W. 6th St.,
Brooklyn, NY (US) 11204

(**) Term: **14 Years**

(21) Appl. No.: **29/264,465**

(22) Filed: **Aug. 11, 2006**

(51) **LOC (8) Cl.** **14-03**

(52) **U.S. Cl.** **D14/138**

(58) **Field of Classification Search** **D14/137,**
D14/138, 147, 218, 341-347, 496; 455/90.3,
455/556.1, 556.2, 575.1, 575.3, 575.4; 379/433.01-433.13;
361/814; 348/14.02

See application file for complete search history.
